Primary Examiner — Philip S Hyder*Assistant Examiner* — Sydney Buffalow(74) *Attorney, Agent, or Firm* — Stetina Brunda Garred & Brucker(57) **CLAIM**

The ornamental design for a mirror attachment for shower head slide bar, as shown and described.

DESCRIPTION

FIG. 1 is a front view of the mirror attachment for shower head slide bar showing my new design;

FIG. 2 is a top view of the invention;

FIG. 3 is a front view of the invention;

FIG. 4 is a bottom view of the invention;

FIG. 5 is a right side view of the invention;

FIG. 6 is a rear side view of the invention; and,

FIG. 7 is a left side view of the invention.

The broken lines shown in the drawings are directed to environment, and are for informational purposes only and form no part of the claimed design.
